United States Patent Office

Des. 216,052

Patented Nov. 18, 1969

216,052

MICROFILM READER

John L. Gianfagna and Eric G. Jansons, Marietta, Ohio,
assignors to Sperry Rand Corporation, New York, N.Y.,
a corporation of Delaware

Filed Dec. 9, 1968, Ser. No. 14,845

Term of patent 14 years

Int. Cl. D16—04

U.S. Cl. D61—1

FIG. 1.

FIG. 2.

FIG. 3.

FIG. 4.

FIG. 1 is a perspective view of a microfilm reader showing our new design;

FIG. 2 is a front view thereof;

FIG. 3 is an elevational view taken from a side thereof; and

FIG. 4 is a top view thereof.

We claim:

The ornamental design for a microfilm reader, substantially as shown.
